US0D1002676S

(12) **United States Design Patent** (10) **Patent No.:** **US D1,002,676 S**
(45) **Date of Patent:** ** **Oct. 24, 2023**

(54) **APPLIANCE**

- (71) Applicant: **Dometic Sweden AB**, Solna (SE)
(72) Inventors: **Mikael Thelin**, Huddinge (SE); **Samuele Meda**, Solna (SE)
(73) Assignee: **Dometic Sweden AB**, Solna (SE)
(**) Term: **15 Years**
(21) Appl. No.: **29/725,866**
(22) Filed: **Feb. 27, 2020**

(30) **Foreign Application Priority Data**

Aug. 30, 2019 (EM) 006786588

- (51) **LOC (14) Cl.** **15-07**
(52) **U.S. Cl.** **D15/81**
USPC **D15/81**

CLAIM

The ornamental design for an appliance as shown and described.

DESCRIPTION

FIG. 1 is a first perspective view of an appliance design;
FIG. 2 is a second perspective view of the design of FIG. 1;
FIG. 3 is a front view of the design of FIG. 1;
FIG. 4 is a first side view of the design of FIG. 1;
FIG. 5 is a second side view top view of the design of FIG. 1; and
FIG. 6 is a top view of the design of FIG. 1.
The broken lines shown in the drawings depict portions of
the appliance that form no part of the claimed design.

1 Claim, 6 Drawing Sheets
